His Attorney.

UNITED STATES PATENT OFFICE

2,045,507

INSTRUMENT PANEL FOR CLOSED
LIQUID HEATERSHenry S. Woodruff, Schenectady, N. Y., assignor
to General Electric Company, a corporation of
New York

Application November 15, 1933, Serial No. 698,121

4 Claims. (CL 73—151)

My invention relates to boiler indicators and particularly to an improved instrument panel for a boiler which is adapted for either the generation of steam or the production of hot water.

For a steam boiler it is ordinarily necessary to provide for indication of the water level and the steam pressure in order that the boiler may be maintained in a safe operating condition. Otherwise the water level may become so dangerously low as to uncover the crown sheet or the steam pressure may become so dangerously high as to rupture the boiler shell. On the other hand, with a boiler used in a hot water heating system it is ordinarily necessary to provide for indication of the water temperature and of the hydrostatic pressure within the boiler in order to maintain the boiler in a safe operating condition. Otherwise the water temperature may reach such a dangerously high value as to create steam or the hydrostatic pressure may become either so extremely high as to rupture the boiler or so extremely low as to interfere with the proper operation thereof. Consequently, when the same boiler may be used at one time in a steam heating system and at another time in a hot water heating system, considerable difficulty arises in providing in any simple manner for the proper indication of the necessary boiler characteristics in each service.

It is the principal object of my present invention to provide an improved form of boiler indicating instrument arrangement which is readily convertible for indicating either the water level and steam pressure for steam heating service or water temperature and hydrostatic pressure for hot water heating service. My present invention is particularly advantageous in that only one set of instrument connecting openings are required in the boiler shell and the different indicating instruments connected thereto as required for both steam and hot water service are enabled to appear in proper registering relationship with the same openings in the enclosing cover. This is of special advantage where the boiler is enclosed within a heat insulating casing.

My invention is described and illustrated herein in its preferred embodiment and as applied to a boiler furnace of the type described in my copending application, Serial No. 676,651, filed June 20, 1933, but it is contemplated that the essential characteristics of my invention may be applied with equal facility and advantages in other embodiments and to other types of liquid heaters.

A clear understanding of the manner in which

I carry out my invention and the advantageous results derived therefrom may be secured from the following description when read in connection with the accompanying drawing in which:

Fig. 1 is a front view of my improved boiler instrument panel as it appears when the boiler is being used for the generation of steam. 5

Fig. 2 is a sectional elevation of the instrument panel of Fig. 1 in its preferred embodiment showing the manner of mounting the elements thereof 10 upon the wall of a boiler, and

Fig. 3 is a sectional plan view along the line 3—3 of Fig. 2, looking in the direction of the arrows as shown.

Fig. 4 is a front view of the instrument panel 15 as it appears when the boiler is being used for the production of hot water,

Fig. 5 is a sectional elevation showing the manner of mounting the various elements of the instrument panel as it is shown in Fig. 4, and 20

Fig. 6 is a sectional plan view along the line 6—6 of Fig. 5 looking in the direction of the arrows there shown.

Referring particularly to Fig. 2 of the drawing, 10 represents a portion of the side wall of a 25 steam and hot water boiler which is provided with an external layer 11 of heat insulating material and an overall sheet metal enclosing casing 12.

An opening 12' is formed in the insulating material and the sheet metal casing 12 opposite 30 an instrument mounting plate 13 which is joined to the wall of the liquid heater by welding or other means as shown at 14. A recess or depression 15, which in my preferred embodiment is in the form of a circular walled groove, is formed 35 in the outer face of the mounting plate 13. This recess is in communication with the interior of the liquid heater by means of threaded passages 16 and 17 in the mounting plate, which passages are in registry respectively with openings 20 and 21 40 in the wall of the liquid heater. The openings 20 and 21 are so placed that they will be positioned in different horizontal planes respectively above and below the normal level of the water in the liquid heater when it is used for the production 45 of steam. A transparent liquid level gage glass of well known design is placed over the recess 15 and is removably held in place by means of clamping flange 23 and screws 24 which engage the screw threaded openings 25 in the mounting 50 plate 13. Packing gaskets 26 are disposed between the clamping flange and the gage glass and between the gage glass and the mounting plate so that the clamping flange may be screwed down 55 tightly to hold the gage glass securely against

the mounting plate to form a fluid-tight chamber within the recess 15.

A threaded passage 27 is provided through the upper portion of the instrument mounting panel 13 and in registering alinement with an opening 28 in the wall of the liquid heater. Mounted in the passage 27 is the connection bushing 29 of a vapor pressure and vacuum gage 30 having a dial face 31 calibrated to indicate vacuum in 10 inches of mercury and vapor pressure in pounds per square inch.

A separate sheet metal cover or panel 33, provided with a circular opening through which may protrude the pressure gage 30 and having a vertical slot 35 provided therein in registering relation with the liquid level gage glass and groove is removably mounted on the plate 13. This cover is removably held in place at the top by means of the bezel ring 32 of the pressure gage and at the bottom by means of a single screw 36 which engages the instrument mounting plate so as to mount the panel 33 in predetermined alignment with the plate 13 with the edges of the panel 33 overlapping the edges of the opening 13' formed 25 in the casing 12, thereby substantially closing said opening as shown in Figs. 2, 3, 5 and 6.

When the liquid heater is used for the generation of steam it will be filled with water to a proper height as indicated by the marker 37 on the cover 33. A small portion of the water in the boiler will flow through the opening 21 and passage 17 into the chamber formed by the recess 15 and the liquid level gage glass 22 and the height of the water in this chamber may be observed on the gage glass as seen through the opening 35 in the cover. Vapor pressure in the chamber 15 will be equalized by means of the passage 16 and opening 20 in the mounting plate and liquid heater wall respectively.

40 When the boiler is to be used in a hot water heating system, the boiler is completely filled with water and hence the water level gage can serve no useful purpose. Therefore, in accordance with my present invention the water level gage 45 glass 22 may be entirely removed from the boiler and a special form of L-shaped thermometer 40 is provided to take the place of the water level gage glass. This thermometer 40 has the bulb leg thereof formed to fit inside of a special well 50 41 which in turn is arranged to form a fluid-tight junction with the openings 17 and 21 formed in the boiler at the bottom end of the water level groove 15. The indicating leg of the thermometer 40 is arranged so that the temperature 55 calibrations thereon register within the slotted opening 35 formed in the cover plate 33.

A description will now be given of the manner in which my improved instrument panel may be converted to give indication of hydrostatic pressure and of water temperature when the boiler is used for the production of hot water. Cover 33, pressure gage 30, and gage glass 22 with its fastening means are removed from the instrument mounting plate. The bulb leg of a special L-shaped thermometer is then inserted into the thermometer well 41 which protrudes into the interior of the liquid heater through passage 17 in the mounting plate and opening 21 in the wall of the liquid heater and which is fastened in place 70 by means of the threaded packing bushing 42 which is screwed into the passage 17. The other end of the thermometer upon which is the temperature indicating scale is held vertically in place by means of spring clips 43 which are secured to the instrument mounting panel by means

of screws 44. A screw threaded plug 45 is then screwed into the passage 16 in the instrument mounting panel to prevent escape of water from the interior of the liquid heater through the opening 20 in the liquid heater wall. An altitude or 5 hydrostatic pressure gage 46 is mounted in the passage 21 in the instrument mounting plate by means of the screw threaded bushing 47, and is provided with a dial face 48 which is calibrated to read in feet pressure head. The instrument 10 panel cover 33 is then mounted as previously described in connection with the use of the liquid heater as a steam generator.

The liquid heater will be completely filled with water and the thermometer 40 which has its bulb 15 submerged therein will be responsive to the temperature of the water which will be indicated on the thermometer scale as observed through the opening 35 in the cover 33. The hydrostatic pressure gage 46 will be responsive to the pressure head within the boiler which will be indicated on the dial face 48.

What I claim as new and desire to obtain by Letters Patent of the United States, is:

1. In combination a convertible steam and hot water boiler having a pair of aligned openings in a side wall thereof, one above and one below the boiler water line, and provided with a water level groove joining said openings, a removable water level gage glass provided with removable 30 fastening means for sealing the glass over said openings and groove, a heat insulating casing for the boiler provided with a removable panel in spaced apart relation with the boiler and having an open slot therein in registering relation 35 with said water gage glass and groove.

2. A convertible steam and hot water boiler having an instrument mounting plate on the exterior of a side wall thereof and provided with a plurality of interchangeable steam and hot water instrument mounting connections communicating with the interior of the boiler, one or more instruments mounted on said plate for indicating boiler conditions, a heat insulating enclosing casing for the boiler having a separately removable panel provided with separate openings for registering with said instruments and provided with means for mounting the panel in a predetermined spaced relation with said instrument mounting plate.

3. A convertible steam and hot water boiler having an instrument mounting plate on the exterior of a side wall thereof and provided with one or more interchangeable steam and hot water instrument mounting connections communicating with the interior of the boiler, a heat insulating enclosing casing for the boiler having an opening therein opposite said mounting plate, one or more instruments for indicating boiler conditions mounted on said plate and extending through said opening, a separately removable recessed instrument panel overlapping the edges of said opening and having separate instrument openings formed therein for registering with said instruments, and means for mounting said panel in a predetermined alignment with said instrument mounting plate to substantially close the opening in said casing.

4. In combination, a convertible steam and hot water boiler having an instrument connection plate joined to the side wall thereof and provided with an opening communicating with the interior of the boiler, a heat insulating enclosing casing for the boiler provided with an opening opposite said plate, a separately removable

panel overlapping the edges of said opening and provided with a vertical slot with the bottom thereof in registering relation with said opening in said plate, and an L-shaped thermometer having means for removably mounting the bulb leg thereof within the boiler through said opening

in said plate with the temperature indicating leg thereof extending in the space between the said plate and panel in registering relation with said slot in said panel.

HENRY S. WOODRUFF. 5
